UNITED STATES PATENT OFFICE.

BUDD G. BEALOR, OF ASPINWALL, PENNSYLVANIA.

METALLIC RAILWAY-TIE.

No. 806,453.

Specification of Letters Patent.

Patented Dec. 5, 1905.

Application filed February 16, 1905. Serial No. 245,888.

To all whom it may concern:

Be it known that I, BUDD G. BEALOR, a resident of Aspinwall, in the county of Allegheny and State of Pennsylvania, have invented a new and useful Improvement in Metallic Railway-Ties; and I do hereby declare the following to be a full, clear, and exact description thereof.

My invention relates to railway-track structures, and more especially to the cross-ties and means for connecting the rails thereto.

The object of my invention is to provide a metallic cross-tie and rail-fastening means which are strong, simple, and cheap of construction and whereby the gage of the track can be adjusted when necessary.

The invention consists in details of construction and arrangement hereinafter described and claimed.

20. In the accompanying drawings, Figure 1 is a plan view of my improved railway-tie and rail-fastening means, showing sections of the rails in place. Fig. 2 is in part a side elevation and in part a central longitudinal section, being taken on the line 2 2, Fig. 1. Fig. 3 is a cross-section on the line 3 3, Fig. 1. Fig. 4 is a longitudinal section, on an enlarged scale, on the line 4 4, Fig. 1; and Fig. 5 is a longitudinal sectional view showing the arrangement on curves.

The cross-tie preferably will be a suitable metallic trough-shaped member placed with its sides projecting upwardly. It is shown in the form of a rolled channel 1, having its web 35. 2, forming the bottom of the trough, and its flanges 3, projecting upwardly and forming the sides. It is obvious, however, that in lieu thereof I may use a plate pressed into trough form and, if desired, it may be provided with outwardly-projecting flanges at the upper edges of its sides. This trough-shaped member is adapted to be embedded in the ballast in the ordinary way, and in order to prevent it moving endwise triangular-shaped portions of its bottom are punched out and bent downwardly to form the projections 5, which take into the ballast underneath the tie and prevent endwise movement of the latter. At the same time the openings 6, formed by 40 punching out the projections 5, serve to drain the trough. As many of these projections 5 may be punched out as are necessary to properly hold the tie in place. These projections are located inside of the rail-bases, so as not 45 to weaken the tie and to be in position to catch into ballast where the latter is solid.

The triangular shape of said projections enables them to embed themselves in solidly-packed ballast.

Underneath the rails are the rail-supporting plates 7, resting upon the edges of the sides 3 of the tie and preferably being provided with shoulders 8 to prevent movement of the plates laterally of the tie. The shoulders 8 may be either inside the trough sides, 60 as shown, or outside the same. If desired, the plate 7 may be set down in recesses formed in the top edges of the trough sides. These plates are provided with slots 9, through which pass fastening-bolts 10, the latter preferably being provided at their lower ends with hooks 11, which take into openings 12, formed in the sides of the tie. At their upper ends these bolts project through openings in rail-securing clamps 14 and have nuts 15 on their 70 outer ends for tightening these clamps.

The clamps 14 may be of any suitable shape to engage the base of the rails. On curves they preferably will be extended upwardly, as indicated at 16, Fig. 5, to also brace the 80 web of the rail and prevent the same from turning. A pair of clamps will be used at each of the rails, these being located on opposite sides of the rail-base and preferably diagonally, as indicated in Fig. 1, although 85 they might be directly opposite each other. The bolts 10 will be inclined diagonally in opposite directions, as shown in Fig. 2, so that when necessary to adjust the gage of the track this can be done by loosening the nut on one 90 of said bolts and tightening the nut on the opposite bolt, thus moving the rail in one direction or the other and bringing the track into exact gage. Generally it will be necessary to loosen the nut for the inner clamp and 95 tighten the one for the outer clamp. The hooked connection of the bolts in the holes 12 and the slots 9 in the plates 7 permit the bolts to swing and accommodate themselves to this adjustment. The faces 17 of the clamps 14, 100 against which the nuts bear, are at right angles to the axes of the bolts, so that the nuts will have a firm bearing against the clamps. A suitable nut-lock (not shown) will be provided.

105 The track construction described is simple and cheap of manufacture and at the same time strong and efficient. The tie member can be any suitable rolled channel member or a pressed plate. No work need be done on it except to punch out the projections 5 in the bottom and the slots or openings 12 in

the sides. The rail-secur ing means can be easily and quickly applied by merely hooking the bolts 10 into the openings 12 and passing them up through the rail-base plates 7. Any ordinary workman can secure the rails in place. Should the track get out of gage, as is liable to happen under severe traffic, it can be easily brought back to gage by merely loosening the nut on one securing-bolt and tightening that on the other securing-bolt, thus moving the rail into its proper place.

Various modifications may be made in the details of construction without departing from my invention. The diagonal arrangement of the fastening-bolts in order to provide for the adjustment of the gage of the track may of course be applied to a cross-tie or base member of any form.

What I claim is—

- 20 1. A railway-track structure comprising a trough-shaped metallic cross-tie, a rail supported thereon with its lower face in proximity to the upper face of the cross-tie, a pair of clamps arranged to engage the rail-base on opposite sides thereof, and a pair of adjustable securing members attached to the sides of the trough-shaped cross-tie near its bottom and projecting diagonally upwardly and in opposite directions and each being connected to a clamp.
- 25 2. A railway-track structure comprising a metallic cross-tie, a rail supported thereon with its lower face in proximity to the upper face of the cross-tie, a pair of clamps arranged to engage the rail-base on opposite sides thereof, and a pair of bolts provided at one end with hooks for engaging the cross-tie near its bottom and projecting diagonally upwardly and in opposite directions and at their outer ends connected to said clamps.
- 30 3. A railway-track structure comprising a cross-tie provided with vertical portions having openings therein, a pair of clamps arranged to engage the rail-base on opposite sides thereof, and a pair of bolts provided at one end with hooks for engaging the openings in the tie and projecting diagonally upwardly and in opposite directions and through openings in said clamps, and nuts on the outer ends of said bolts engaging said clamps.

4. A railway-track structure comprising a metallic trough-shaped cross-tie, a rail-base plate adapted to support the rail, said plate resting on the top of said tie and provided with slots whose axes are substantially parallel with the axis of the tie, a pair of clamps arranged to engage the rail-base on opposite sides thereof, and a pair of holding-rods connected at one end to said tie and projecting diagonally upwardly and in opposite directions and through the slots in the rail-base plate and being adjustably connected to said clamps. 55

5. A railway-track structure comprising a metallic cross-tie provided with vertical portions having holes therein, a rail-base plate 65 resting upon said tie and provided with slots, a pair of clamps arranged to engage the rail-base on opposite sides thereof, and a pair of bolts provided at one end with hooks for engaging the openings in the tie, said bolts projecting diagonally upwardly and in opposite direction and through the slots in the rail-base plates, and each being connected to a clamp. 70

6. A railway-track structure comprising a metallic trough-shaped cross-tie adapted to be 75 placed with its sides projecting upwardly and provided with openings in its sides, rail-base plates resting on the upper edges of said trough-shaped member and provided with slots, a pair of clamps arranged to engage the 80 rail-base on opposite sides thereof, and a pair of bolts connected to said tie and projecting diagonally upwardly and in opposite directions and through the slots in the rail-base plate and 85 through openings in the clamps, and nuts on the outer ends of said bolts and engaging said clamps.

7. A railway cross-tie comprising a trough-shaped metallic member adapted to be placed with its sides projecting upwardly and having 90 triangular portions of its bottom between the rail-seats punched out and bent downwardly to form holding means and drain-openings.

In testimony whereof I, the said BUDD G. BEALOR, have hereunto set my hand.

BUDD G. BEALOR.
